UNITED STATES PATENT OFFICE.

PERLEY H. ROBERTS, OF ROCHESTER, NEW HAMPSHIRE.

TOOTH-BRUSH HOLDER.

1,084,965.

Specification of Letters Patent.

Patented Jan. 20, 1914.

Application filed October 14, 1912. Serial No. 725,656.

To all whom it may concern:

Be it known that I, PERLEY H. ROBERTS, of Rochester, in the county of Strafford and State of New Hampshire, a citizen of the United States, have invented a new and useful Improvement in Tooth-Brush Holders, of which the following is a specification.

My invention relates to a tooth brush holder in the nature of a container inclosing the brush, including its handle.

The object of my invention is to provide a holder of the above character made up of separate parts which combine with one another to form a container for holding the brush, each of which separate parts is carried by a fixture that may be secured to a wall or other suitable support, and by which the parts are held securely and permanently in place, that is, until detached from the fixture; to provide, also, whereby the separate parts of the container may combine to coöperate with one another in an opened or closed position which determines the opening and closure of the container, and when in a closed position to hermetically seal the brush contained within the same, either for the retention of vapors which may rise from some antiseptic matter placed within the container for the purpose of sterilizing the brush, or for sealing the brush against atmospheric or other outside deleterious influences.

It is a further object of my invention to provide whereby the separate parts forming the container may be easily detached from the fixture for purposes of cleansing and may also be easily cleansed. It is also necessary as I have provided that the device should be as simple as possible in the number, form and disposition of its parts.

The holder embodying my invention can best be seen and understood by reference to the drawings, in which—

Figure 1 is a side elevation of the holder. Fig. 2 is a cross vertical section thereof.

In the drawings 1 and 2 represent respectively the body and cover of the receptacle or container adapted to receive and inclose the brush. The body 1 of the receptacle presents a narrow elongated vessel preferably cylindrical in form, having a closed bottom and open top. Just adjacent to the top edge thereof the body is provided with a bead or shoulder 3 forming a flange which

assists in the support and retention of the body as will afterward be explained. The body presents an interior chamber adapted to inclose the major portion of the brush.

Fitting upon the body 1, the cover 2 presents a domelike structure having the same general form as the body though much shorter in length inasmuch as the interior of the cover is designed to inclose that portion only of the brush that extends above the body and is left uninclosed thereby. At the bottom end thereof the wall is properly thickened in order that it may coöperate with or engage the top end of the body widened by the flange 3 as aforesaid. On the inside the cavity or chamber formed within the cover is such as to so continue or extend the chamber formed within the body that the combined parts will inclose the entire brush including its handle. The interior surfaces forming the chamber thus provided in both the body and cover present also smooth interior walls capable of being easily cleansed when the parts are separated.

A tight joint is established between the parts when the cover is applied to the body simply by resting thereon. The parts are made of glass and where the cover rests upon the body the meeting edges are ground forming a tight joint.

The parts 1 and 2 forming the container are carried by a bracket 4. This bracket consists of a main or body portion 5 provided with branches 6 bearing flanges 7 by which the bracket may be secured to a wall or other suitable supporting base.

Connecting with the main portion 5 of the bracket are arms 8 and 9 respectively. Of these arms the arm 8 is a fixed arm bearing upon its end a holding ring or support 10 through which the body 1 of the container is adapted to extend and rest thereon by its flanged end 3 engaging said ring or support. The arm 9 of the bracket is a pivoted arm the same being secured to the main portion 5 of the bracket by a hinged connection 11. The arm 9 is a curved arm bearing upon its end a ring or support 12 through which the cover 2 is adapted to extend and fit snugly therein, and be held by frictional engagement between the parts. The form, disposition and arrangement of the arm is otherwise such that the cover carried thereby may be turned to a closed position where

it will properly coincide with the body of the container covering the same and form a tight joint therewith as aforesaid, or be turned to an open position away from the body of the container as indicated in the dotted line shown in the drawing.

For the purpose of holding the cover in its closed and opened positions the bracket may as shown be provided with a spring 13 arranged to draw against the end of the arm 9 and engage edges 14 and 15 respectively, formed thereon, which determine the closed and open positions of the cover.

When the cover is turned back to an open position both it and the body of the container may be removed from the bracket. Under ordinary circumstances, however, the cover need not be removed from the bracket for it can be readily cleansed while affixed thereto. Owing to the fact that the body of the container is of considerable depth it is more convenient to remove it from the bracket for purposes of cleansing and such removal may very easily be obtained, simply by lifting the body out of the bracket.

I prefer that the container shall be provided with a buffer 16 of some suitable material placed in the bottom thereof on which

the brush may stand although this is not necessary.

What I claim as my invention is:

A tooth brush holder consisting in part of a container for inclosing the entire brush, the same composed of a chambered body portion and a chambered cover adapted to co-operate with said body portion by resting thereon and forming a tight joint, a bracket carrying said body portion and cover, said bracket having separate arms with rings carried thereby, one of said arms being a fixed arm through the ring of which said body portion of the container is adapted to extend and rest in part thereon, the other of said arms being a pivoted arm through the ring of which said cover passes to have engagement therewith and be retained thereby, and means for pivotally securing the arm carrying said cover whereby it may be turned to positions corresponding with the turned open and closed positions of said cover with respect to said body.
